UNITED STATES PATENT OFFICE.

PHILLIPS PAYSON BOURNE, OF WINCHESTER, MASSACHUSETTS, ASSIGNOR TO WORTHINGTON PUMP AND MACHINERY CORPORATION, OF NEW YORK, N. Y., A CORPORATION OF VIRGINIA.

OIL-ENGINE-DRIVEN CENTRIFUGAL AND SIMILAR PUMP.

Application filed November 6, 1924. Serial No. 748,011.

This invention relates to the control of internal combustion engines and especially to an improved control for internal combustion engines driving centrifugal pumps or the like, 5 and is especially adapted for use in installations drawing water from rivers or the like where there is or may be a considerable variation in the water level.

This condition prevails to a great extent in 10 irrigation installations where any variation in the suction level results in a corresponding variation in the quantity of water discharged by the pump. In installations of this type the most economical and efficient operation is 15 that in which the pump delivers a uniform quantity of water irrespective of supply level with a minimum of fuel consumption in the engine, and this quantity of water delivered by the pump is preferably the maximum discharge within the horse power or mean pressure limits of the engine. The present day 20 governor or speed responsive control maintains the normal speed of the engine substantially constant without regard to the load thereon and in order to maintain the desired 25 uniform pump delivery it is necessary to provide means for varying the normal speed of the engine to correspond to the various changes in the pump suction water level.

One object of this invention is to provide 30 an improved control for the internal combustion engine of a centrifugal or similar non-displacement pump, by which the normal speed of the engine may be varied, in accordance with changes in the pump suction level, to that speed required at each suction level for maintaining the pump discharge uniform throughout the various changes in suction level.

A further object is to provide a simple and 40 efficient control of general application in internal combustion engines combining a speed responsive control of the fuel for maintaining a constant normal speed with an adjustable control determining the speed which the governor shall maintain constant, and I preferably include in the combination an adjustable control for fixing a variable limit on the maximum of fuel that can be fed to the engine at the different normal speeds for which the engine is adjusted.

For a full understanding of the invention, constructions embodying all the features thereof will now be described in detail in con-

nection with the accompanying drawings 55 forming a part of this specification and the features forming the invention then specifically pointed out in the claims.

In the drawings,—

Figure 1 is a side elevation of an internal 60 combustion engine driven centrifugal pump unit.

Figure 2 is a section through the internal combustion engine control box.

Figure 3 is a section on a line 3—3 of Fig. 2. 65

Figure 4 is a section, partly in elevation, on line 4—4 of Fig. 2.

Figure 5 is a side elevation of a detail, and

Figure 6 is a side elevation, partly dia- 70 grammatic, of a modification.

Referring to the drawings, the centrifugal pump A may be directly connected to the internal combustion engine B by a suitable flexible coupling C to form a unit therewith and the operation of the internal combustion 75 engine is controlled by mechanism mounted within a control box D secured at one end thereof, and on which is mounted the fuel pump body E comprising a plurality of fuel pumps, one for each cylinder of the engine. 80

As shown in Figures 2 and 3, each fuel pump comprises the usual pump plunger 7 and suction and discharge passages 1, 2, controlled respectively by suction valve 3 and discharge valve 4. The suction passage 1 85 connects with a fuel supply chamber 5 common to all the pumps and the discharge passage 2 connects with one of the engine cylinders through the piping 6. The pump plunger 7 is suitably actuated, as by tappet 8 moved 90 by engagement with the roller 9 of a strap eccentric 10 mounted on the engine crank shaft 11 which extends within the control box D. The pump has a variable delivery which

is of the suction by-pass type in which the 95 suction valve 3 is held open during a varying time in the latter portion of the stroke of the plunger 7 by means of a by-pass plunger 12 moved by by-pass tappet 13 at the proper time. The by-pass tappet 13 is moved by 100 the movement of plunger tappet 8 through a by-pass lever 14 pivoted at one end to the plunger tappet 8 and having its opposite end resting upon an eccentric fuel control shaft 15 adjustable under the control of a speed 105 responsive device to determine the time and period of opening of the suction valve 3 for by-passing the fuel.

The speed responsive device comprises a governor base 16 secured to the engine crank shaft 11 and mounting pivotally weights 17 which have arms bearing against a sleeve 18, 5 axially movable on the crank shaft 11 and provided with shrouds 19 between which the forked ends 20 of a bifurcated lever 21 extend. The bifurcated lever 21 is secured to and supported by a shaft 22 to which is also 10 secured a governor lever arm 23 connecting with the lower end of an adjustable link 24, preferably by a sliding joint formed by forked the end of the lever arm 23 and connecting the forked ends by a pivotal bolt 24' and 15 providing a passage through the bolt 24' through which the adjustable link 24 passes freely, a head 25 on the end of the link 24 co-acting with the governor lever arm 23 for movement of the link 24 downward. The 20 upper end of the adjustable link 24 is pivoted to one end of a lever 26, the opposite end of which is secured to the eccentric fuel control shaft 15.

The lever 26 comprises a hub 27 secured to 25 the eccentric fuel control shaft 15 by a pin 28 and provided with two parallel lever arms connected at their outer ends by a pivot pin 30 rotatable therein to which is secured the forked end 31 of the adjustable link 24. A 30 light spring 32 secured at one end to control box D and at the other to an eye 33 carried by pin 30 holds the head 25 of the adjustable link 24 in engagement with the governor lever arm 23.

35 The maximum amount of fuel which can be injected into the engine at any time is adjustably fixed by providing the hub 27 with a peripheral recess 34 forming a shoulder 35 which co-acts with a pin 36 carried by a hand lever 37 loosely mounted upon the eccentric fuel control shaft 15 between the hub 27 and the control box D. The hand lever 37 is moved by a handle 38 and is secured in the desired position by a bolt 39 and a thumb 40 screw 42 which clamp upon an arcuately slotted plate 40 secured to the control box D by bolts 41.

45 As is usual in speed responsive or governor controlled engines, the governor controls the fuel injection to maintain the normal speed of the engine regardless of the changes in load no matter from what source these changes may arise. In the present invention I provide means for modifying the action of the governor 50 by adding to or decreasing the strength of the governor spring to provide different new speeds for the engine which the governor will then operate to maintain constant. In the construction shown and described, my 55 invention is applied to an irrigation installation to secure a pump discharge which will be uniform throughout the various changes in pump suction level coincident to such use.

60 For this purpose, as shown in Figures 1 to 65 5, inclusive, I extend the governor lever arm

23 beyond the shaft 22, that is to the side opposite the adjustable link 24 and place thereon a suitable weight 43 which by its position on the lever arm 23 at one side or the other of the shaft 22 will determine the speed above or 70 below normal which the governor will now operate to maintain constant. The weight 43 may be secured in adjusted position by any suitable means, as by screw bolt 44.

75 The operation is as follows:

As the engine speeds up the governor weights 17 move outward drawing lever 26 downward against the action of spring 32 through parts 23 and 24 to rotate the eccentric fuel control shaft 15 suitably and raise the outer end of the by-pass lever 14 whereby the movement of the plunger tappet 8 causes the suction valve 3 to be opened earlier in the pump plunger stroke, securing the desired decrease in the fuel supply to the engine 80 to that quantity which is necessary to maintain the normal speed of the engine under its normal load. Upon a decrease in the engine speed, whether from overload or otherwise, the governor will re-establish the normal 90 speed of the engine by an inward movement of the weights 17 which allows the spring 32 to move the eccentric fuel control shaft 15 in the opposite direction, thus lowering the outer end of the by-pass lever 14 producing a later opening of the suction valve 3 for bypassing and thus increasing the supply of fuel to the engine cylinders. The increase in the fuel supply to the engine is dependent not only on the governor but also on the position of the pin 36 and the engagement therewith of shoulder 35 which adjustably fixes the maximum quantity of fuel which can be injected and thus prevents fouling of the engine, the governor being inoperable above 100 this point, and this maximum feed may so reduce the speed that the governor does not control at such speed.

105 The normal speed to be maintained by the governor control may be varied by aiding or opposing the movement of the governor by any suitable means. In the construction shown for the purpose of illustration, the normal speed of the engine may be varied at will by adjusting the position of the weight 110 43 along the governor lever arm 23, and the governor will then act to maintain the new normal speed constant. By securing the weight 43 outside the shaft 22 the normal speed is increased to any desired extent as the weight 43 then aids the governor action tending to increase the fuel feed, and by securing at any point along the lever arm 23 between the shaft 22 and the adjustable link 24 the normal speed is decreased to any desired 115 value, as the weight 43 then opposes the governor action and tends to retard the governor movement on increase of speed.

120 The construction shown in Figures 1 to 5 is adjusted by hand, but various forms of 130

automatic control of the normal speed may be used, such forms depending upon the type of engine and the conditions under which the engine is to operate.

5 Thus in Figure 6 I have shown diagrammatically a construction in which the pump suction level automatically adjusts the normal speed of the engine to correspond to the pump suction level. In this construction the 10 weight 43 is connected by link 45 to the end of the long arm of a T-lever 46 pivotally secured to the control box D by pivot bolt 47. To one arm of the lever cross bar is secured the cable 48 which passes about suitable pulleys 49 and is secured at its opposite end to the float 50. Upon the opposite arm of the 15 lever cross bar is secured a suitable weight 51. Upon a decrease in the pump suction level the float 50 moves downward and operates 20 through cable 48, lever 46, and link 45 to move the weight 43 outward to increase the normal speed of the engine correspondingly to maintain the pump discharge uniform. When the water level increases the float 50 slacks off on 25 the cable 48 and the weight 51 operates to move the weight 43 inward along the governor lever arm 23 thus correspondingly decreasing the normal speed of the engine.

An advantage of the constructions shown 30 resides in the fact that they may readily be attached to any engine control box, but it will readily be understood that the invention is not to be limited to the constructions shown, as many modifications thereof may be made 35 within the invention as defined by the claims.

What is claimed is—

1. The combination with an internal combustion engine and a centrifugal or similar pump driven thereby and automatic fuel control devices for the engine, of adjustable means controlled by the pump suction head to automatically vary the engine speed on changes in said head to maintain a uniform discharge by the pump. 40

2. The combination with an internal combustion engine and a centrifugal or similar pump driven thereby and automatic fuel control devices for the engine including a governor for maintaining a constant normal engine speed, of adjustable means controlled by the pump suction head to automatically vary the normal engine speed on changes in said head to maintain a uniform discharge by the pump. 45

3. The combination with an internal combustion engine and a centrifugal or similar pump driven thereby and automatic fuel control devices for the engine including a governor for maintaining a constant normal engine speed, of a weight adjustable to aid or oppose the governor action, a float controlled by the pump suction head, and connections between the weight and float whereby the normal engine speed is automatically varied on change in said head to maintain a uniform 50 discharge by the pump. 55

In testimony whereof, I have hereunto set my hand.

PHILLIPS PAYSON BOURNE.
